[57] ABSTRACT

A container which can be easily filled and handled for the packing of two compositions which must be separately kept until mixed shortly before use, consists of two separate chambers which are arranged one upon the other in a packing unit. The upper chamber is provided with a closeable orifice for the delivery of the mixture. An intermediate part is arranged between the two chambers and such part has cutting edges or sharp mandrels on both sides thereof which allow the two compositions being separately kept to be mixed by cutting the bottom part of the upper chamber and the upper part of the bottom chamber when the container is pressed or screwed together.

TWO COMPARTMENT CONTAINER**CROSS REFERENCE TO RELATED APPLICATION**

The present application is a division of application Ser. No. 101,374, filed Sept. 25, 1987 now U.S. Pat. No. 4,801,009.

BACKGROUND OF THE INVENTION

The present invention relates to a container for the packing of two compositions which must be separately kept until being mixed shortly before use.

Two compartment containers have long been known. Normally, they consist of two separate chambers which are arranged one upon the other in a packing unit. The upper chamber is provided with a closeable orifice for the delivery of the mixture. Both containers are separated by a separating foil which is penetrated by a sharp-edged punching tool in the container, when the containers are screwed or pressed together. This allows the container contents to mix shortly before use. Such a two compartment packing unit is described in German Pat. No. 2,760,079.

Further arrangements of known two compartment containers are disclosed in German Offenlegungsschriften Nos. 2,451,167, 1,536,305, 2,211,753, and 2,539,231, U.S. Pat. Nos. 3,521,745 and 3,548,562, and German Utility Model No. 7317067.

The filling of two compartment packings with the compositions to be separately kept until their use is normally effected in such a way that first the bottom container is filled with the corresponding product, then its opening is welded with a separating foil to the upper container which is then filled and closed. Such a procedure consisting of several steps is rather complicated and expensive.

Another disadvantage of the known two compartment containers is that the opening mechanism, i.e. a mandrel or a corresponding cutting edge causing the penetration of the separating foil, has to be fixed in one of the two chambers and is thus permanently in contact with its filling. This might cause unwanted modifications of the product when it is stored for a long time. Thus, there existed a need to develop a two chamber packing which does not have these disadvantages.

SUMMARY OF THE INVENTION

It has now been found that in case of two compartment containers according to the above described type, these disadvantages can be avoided according to the present invention. Between the two chambers an intermediate link is arranged provided on both sides with cutting edges or mandrels, which when the two chambers are pressed or screwed together, simultaneously cut the bottom part of the upper chamber and the upper part of the bottom chamber. This allows the separately kept compositions to be mixed together and then subsequently released from the container as the product mixture.

BRIEF DESCRIPTION OF THE DRAWINGS

Novel features and advantages of the present invention in addition to those noted above will become apparent to those of ordinary skill in the art from a reading of the following detailed description in conjunction

with the accompanying drawings wherein similar reference characters refer to similar parts and in which:

FIG. 1 is a side elevational view of a two compartment container, according to the present invention;

FIG. 2 is an exploded longitudinal sectional view of the container shown in FIG. 1;

FIG. 3 is a partial longitudinal sectional view of the two compartment container of FIGS. 1 and 2 illustrating the container in its stored position prior to use;

FIG. 4 is a partial exploded longitudinal sectional view of another embodiment of the invention; and

FIG. 5 is a partial longitudinal sectional view of the container of FIG. 4 illustrating the container in its stored position prior to use.

DETAILED DESCRIPTION OF THE INVENTION

FIG. 1 illustrates an integrated two compartment container having a screw cap 1 arranged on top of an upper container compartment 2. The two compartment container also includes a bottom container compartment 3 as well as an intermediate part 5 provided with a screw element containing an opening mechanism in the form of cutting edges or sharp mandrels on both sides.

The upper part 2 is connected with the bottom part 3 through the intermediate part 5 which is provided with two packing rings 4 and two cutting rings 8. The upper part 2 is sealed with a foil 6 at its bottom side and the bottom part 3 is sealed with foil 6 at its upper opening. This foil preferably consists of aluminum which is plastic-coated on both sides and connected to the container material by welding.

The upper part 2 has internal threads 9 which cooperate with external threads 7 on the lower part. With these cooperating threads the intermediate part 5 can be moved in such a way that the cutting elements 8 destroy the foils 6 thus allowing the contents of the container compartments 2 and 3 to be mixed.

The destruction of the foils 6 by the cutting elements 8 or analogously arranged mandrels might of course also be provided by an elastic arrangement of the intermediate part 5 which allows the containers being pressed together. Also, the upper part 2 does not have to be sealed by a screw cap, but might be closed by any known seal.

The two compartment container according to the invention is particularly suitable for the delivery of hair dyes on the basis of oxidation dyes and peroxides which must be separately kept until their use.

FIGS. 4 and 5 show an alternate embodiment of the invention wherein similar reference characters are used to identify similar parts. The upper and lower container compartments 2, 3 are sealed by foil 6 in the same manner as the two compartment container of FIGS. 1-3, and the intermediate part 5 is disposed between the foils. A rotatable operator or sleeve 10 is on the outside of upper part 2. Sleeve 10 has internal threads 9 that cooperate with external threads 7 on the lower part 3, and the sleeve is constructed and arranged to rotate relative to both the upper and lower parts. When the sleeve 10 is rotated, the upper and lower container compartments are drawn together until the cutting elements 8 pierce the foils 6 thereby allowing the contents to mix. The upper compartment or chamber 2 has an upwardly opening annular channel on the outside thereof while the rotatable operator or sleeve 10 includes a down-

wardly extending cylindrical annulus that fits within the annular channel in snap-fitted engagement therewith.

I claim:

1. A container for packing two compositions which must be separately kept until being mixed together shortly before use, the container consisting of two separate chambers arranged one upon the other and movable toward and away from one another, the upper chamber having a closeable orifice for delivery of the container contents, means sealing the upper and lower chambers, and an intermediate part arranged between the two chambers, the intermediate part having means for cutting the sealing means of the upper and lower chambers when the chambers are moved toward one another to thereby allow mixing of two compositions 15 being separately kept, one composition in each of the

two chambers, and an operator on the outside of the upper chamber constructed and arranged to rotate relative to the upper chamber and to move that chamber toward the lower chamber, the upper chamber having an upwardly opening annular channel on the outside thereof, the operator including a downwardly extending cylindrical annulus that fits within the annular channel, internal threads on the operator and cooperating external threads on the lower chamber whereby the chambers move toward one another when the operator is rotated.

2. A container as in claim 1 including a snap-fit between the annular channel on the outside of the upper chamber and the downwardly extending cylindrical annulus of the operator.
